CLAIM

The ornamental design for a paper or towel dispenser, as shown and described.

DESCRIPTION

FIG. 1 is a perspective view of a paper or towel dispenser of the new design;

FIG. 2 is a front elevation view of the paper or towel dispenser shown in FIG. 1;

FIG. 3 is a rear elevation view of the paper or towel dispenser shown in FIG. 1;

FIG. 4 is a top plan view of the paper or towel dispenser shown in FIG. 1;

FIG. 5 is a bottom plan view of the paper or towel dispenser shown in FIG. 1;

FIG. 6 is a left-side elevation view of the paper or towel dispenser shown in FIG. 1; and,

FIG. 7 is a right-side elevation view of the paper or towel dispenser shown in FIG. 1.

The broken lines shown in the figures represent portions of the paper or towel dispenser that form no part of the claimed design. The break lines in the drawings indicate that any portion of the article beyond what is shown forms no part of the claimed design.

The bold, wavy lines shown in the drawings represents boundaries to the claimed design and forms no part of the claimed design.
